UNITED STATES PATENT OFFICE.

WILLIAM H. BENDER NAGEL, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE TRANSMISSION SYSTEM.

Application filed December 6, 1919. Serial No. 343,011.

To all whom it may concern:

Be it known that I, WILLIAM H. BENDER NAGEL, a citizen of the United States, residing at Queens, in the county of Queens, 5 State of New York, have invented certain new and useful Improvements in Telephone Transmission Systems, of which the following is a full, clear, concise, and exact description.

10 This invention relates to telephone transmission systems and more particularly to such circuits in which repeaters are employed. The object of the invention is to provide an amplifying repeater in a subscriber's telephone line circuit.

One of the features of the invention is the provision of means for causing the operation of a cut-off relay to disconnect the line relay from the line and simultaneously to 20 connect battery to the filament of the repeater to render the same operative. Another feature is to render the repeater operative when the operator answers a subscriber's call. Another feature is to connect the subscriber's line with a relay for controlling the supervisory signal of the connected cord or link circuit.

Other features and advantages of the invention will be obvious as the description 30 proceeds. The invention will be readily understood from the description in connection with the drawings in which three embodiments of the invention are illustrated.

In the drawings:

35 Fig. 1 shows a line circuit in which a single one-way amplifier is employed and in which provision is made for ringing from a switchboard through the hybrid coils associated with the amplifier.

40 Fig. 2 shows a line circuit equipped with a single one-way amplifier provided with an apparatus whereby when an operator rings a subscriber, the amplifier is disconnected and the ringing current passes directly 45 through to the subscriber's station.

Fig. 3 is similar to Fig. 2, except that the subscriber's line circuit is equipped with two one-way repeaters.

50 In each of the embodiments of the invention is shown means by which the subscriber can flash a signal lamp to call the operator whether the plug is in the subscriber's jack or not, and also for permitting the operator to ring the subscriber as is common.

55 The invention will be particularly de-

scribed in connection with Fig. 1 and will be more briefly described in connection with the other figures. In Fig. 1 at A is indicated a subscriber's telephone set of the usual construction, having the primary of a transformer 6 in circuit therewith. The subscriber's line circuit extends through the transformer 6 and connections, which will be described below in detail, to jack J at the central station.

When the subscriber A removes his receiver, a circuit is closed from ground through battery and relay 1, primary of transformer 6, subscriber's transmitter, back to ground. The consequent energization of 60 relay 1 causes the lighting of the line lamp 2, over an obvious circuit. Thereupon the operator inserts the plug P of the cord circuit into the jack J, thereby closing a circuit from ground through the battery and lamp 4, sleeve contacts of plug P and jack J, through relay 3 to ground. Relay 3 becomes energized, and at its left-hand back contacts cuts off the line relay 1 which releases and thus extinguishes the line lamp 2. 65 The right-hand forward contact of relay 3, is also closed by the energization of said relay. The relay 3 closes at its left-hand forward contacts a circuit from ground and battery through relay 5 and the subscriber's set back to ground. The energization of relay 5 closes a circuit from ground and battery through the forward contact of relay 5 and through relay 3 to ground, thereby shunting 70 and extinguishing the supervisory lamp 4. 75 The closing of the right-hand contact of relay 3 supplies heating current to the filament of the bulb R to ground.

The apparatus is now in condition for 80 amplifying outgoing currents from the subscriber A as follows: Transmission currents from subscriber A pass through the primary of transformer 6 where it is transformed through the secondary of transformer 6 and circulates in the circuit comprising 85 the secondary of transformer 6 and the neutralizing balancing network N and the primary of transformer 7. The balancer N maintains the points 8' and 8'' at equal potentials, so that none of the current passes 90 through the primary of transformer 8. The current passing through the primary of transformer 7 is transformed to the secondary from whence it passes through the 95 input side of repeater R, where it is amplified 100 to the subscriber A. The supervisory 105 lamp 4 is connected in series with the primary of transformer 7, so that it is illuminated whenever the subscriber A is 110 connected to the line.

fied and passes to the points 7', 7'', thence through the jack J and plug P to the cord circuit.

Either ringing or talking current passes from the cord circuit through the plug and jack to the subscriber A without being amplified as follows: from jack J through the circuit comprising the neutralizing balancing network N' and the primary of transformer 8. The points 7', 7'' being maintained at the same potentials by the balancer N', no current passes to the repeater R, but is transformed to the secondary of transformer 8 from which it passes to the points 8', 8'', thence through the transformer 6 to the subscriber A.

When the plug P is in the jack J, the subscriber A can flash the supervisory signal light 4 by moving his hook up and down. This operation is possible because the successive opening and closing of the circuit through the subscriber's set energizes and de-energizes the relay 5, thereby vibrating its armature to open and close the circuit from ground through contact of relay 5 and the relay 3. It is thus seen that the subscriber A may signal the operator when the plug P is in the jack J through the supervisory lamp 4, and may signal her through the line lamp 2 when the plug is out of the jack.

Withdrawal of the plug P from jack J before the subscriber hangs up his receiver does not render the repeater inoperative because even with the plug out, current continues through relay 3 from contact of relay 5, thus maintaining the filament of the repeater active until the subscriber hangs up. Likewise hanging up of the subscriber's receiver while plug P is in jack J will not cut off the current from the filament, since current is maintained from battery through lamp 4, sleeve contacts of plug and jack, through relay 3 to ground.

In Fig. 2 parts similar to those shown in Fig. 1 are designated by similar reference figures, except that the subscript 2 is used. The operation of identical parts in the two figures are exactly alike so it is deemed unnecessary to describe the same in detail in connection with this figure. In addition to the apparatus of Fig. 1, the embodiment shown in Fig. 2 is provided with the relay 9₂ and the relays 10₂, 10'₂, together with the connecting lines 11₂. When alternating or pulsating ringing current comes through jack J₂, relay 9₂ is energized, thereby permitting current to flow from ground and battery, through relays 10₂, 10'₂ in parallel and contact of relay 9₂ to ground, thus closing the inner, upper and lower contacts of relays 10₂, 10'₂ and cutting off the repeater and associated parts, so that ringing current goes directly to the bell of subscriber A₂ through line 11₂ from jack J₂.

In Fig. 3, parts similar to those shown in

figs. 1 and 2 are designated by similar reference characters, except that the subscript 3 is used. The operation of identical parts in Fig. 3 is exactly the same as in Fig. 2, so it is deemed unnecessary to explain the same in detail. In addition, the embodiment shown in Fig. 3 is provided with another repeater R'₃, so that both the outgoing and the incoming talking current is amplified. The amplification of the outgoing talking current has already been explained in connection with Fig. 1. The incoming talking current passes through ring and tip contacts of jack J₃ and through the circuit comprising the neutralizing balancing network N'₃ and the primary of transformer 8₃ where it is transformed to the secondary of transformer 8₃ passes through the input circuit of repeater R'₃, where it is amplified and passes through the output circuit of the same to the points 8'₃ and 8''₃, and then through the transformer 6₃ to the subscriber's set A₃. The points 7'₃, 7''₃ and 8'₃, and 8''₃ are maintained at equal potentials by the balancers N'₃ and N₃ respectively, so that outgoing talking current is forced to pass through repeater R₃ and incoming talking current is forced to pass through R'₃.

What is claimed is:

1. In a telephone system, a subscriber's line terminating at a central switchboard, a link circuit, an amplifying repeater in said line, and means for causing ringing current to cut out said repeater and connect said link circuit directly to said subscriber's bell.

2. In a telephone system, a subscriber's line terminating at a central switchboard, a link circuit, an amplifying repeater in said line, and a relay operable by ringing current to alter connections so as to cut out said repeater and establish direct connection from said link circuit to said subscriber's bell during the application of ringing current.

3. In a telephone system, a subscriber's line terminating at a central switchboard, a repeater in said line, a link circuit, and means for rendering said repeater operative upon connecting said link circuit to said line, and means for cutting out said repeater and establishing direct connection between said link circuit and the subscriber's bell by ringing current from said link circuit.

4. In a telephone system, a subscriber's line terminating at a central switchboard, a repeater in said line, a link circuit, and means for rendering said repeater operative upon connecting said link circuit to said line, and a relay operable by ringing current to alter connections so as to cut out said repeater and establish direct connection from said link circuit to said subscriber's bell during the application of ringing current.

5. In a telephone system, a subscriber's line including a line relay and cut off relay

- associated with said line; a link circuit; an amplifier in said subscriber's line; a supervisory signal; a relay for controlling said signal; and means whereby 5 operation of said cut off relay disconnects the line relay from the line, renders the repeater operative, and connects the supervisory relay with said subscriber's line.
6. A local subscriber's line terminating at 10 one end at a central switchboard, a local subscriber's substation set at the other end of said line, a vacuum tube in said line, and means directly controlled by the operation of connections at said set for controlling said 15 tube independently of voice currents in said line.
7. In combination, a line section, a second line section, a balancing artificial line for each of said lines, a three-winding transformer having one winding in said first line section and a second winding in the corresponding artificial line, a second three-winding transformer having a winding in said second line section and a second winding in the corresponding artificial line, connections between the third winding of said first transformer and midpoints of the two mentioned windings of said second transformer, connections between the third winding of said second transformer and the midpoints of the two first-mentioned windings of said first transformer, and an amplifying repeater in only one of said connections. 20
8. In an electric system, a local subscriber's line terminating at one end in a local subscriber's substation set and at the other end terminating in a central office at which a plurality of lines terminate, a link circuit at 25 said central office adapted to interconnect said first line with another line, a normally inoperative amplifying repeater in said first line, means controlled by the connection of said link circuit to said first local line for rendering said repeater operative, and for maintaining said repeater operative even after said link circuit is disconnected from 30 said line, and means controlled by the disconnection of an element of said subscriber's set from said first line for rendering said repeater inoperative.
9. In an electric system, a local subscriber's line terminating at one end in a local subscriber's substation set and at the other end terminating in a central office at which a plurality of lines terminate, a link circuit at 35 said central office adapted to interconnect said first line with another line, a normally inoperative amplifying repeater in said first line, means controlled by the connection of
- said link circuit to said first line for rendering said repeater operative, and means responsive to the disconnection of the receiver of said subscriber's set from said first line for rendering said repeater inoperative after said link circuit has been disconnected from 40 said first line.
10. In an electric system, a local subscriber's line terminating at one end in a local subscriber's substation set and terminating at the other end in a central switchboard, a link circuit adapted to be connected to the switchboard end of said line, a normally inoperative repeater in said line, a supervisory relay, a supervisory signal controlled by said 45 relay, a cut-off relay controlled by the connection of said link circuit to said line, and connections whereby the operation of said cut-off relay renders said repeater operative and places said supervisory relay under the control of said subscriber's line. 50
11. In an electric system, a local subscriber's line terminating at one end in a local subscriber's substation set and terminating at the other end in a central switchboard, a link circuit adapted to be connected to the switchboard end of said line, an amplifying repeater between said set and said link circuit, a line relay responsive to a signal from said subscriber's set, signaling means controlled by said relay, a supervisory signal, and means controlled by the connection of said link circuit to said local line for rendering said repeater operative, for disconnecting said line relay from said line, and for placing said supervisory signal under the control of said subscriber's set. 55
12. In an electric system, a local subscriber's line terminating at one end in a local subscriber's substation set and terminating at the other end in a central switchboard, a link circuit adapted to be connected to the switchboard end of said local line, a normally inoperative amplifying repeater in said local line, a line relay controlled by a signal from said subscriber's set, signaling means controlled by said line relay, a supervisory relay, a supervisory signal controlled by said supervisory relay, and a cut-off relay controlled by the connection of said link circuit to said local line for rendering said repeater operative, for disconnecting said line relay from said line, and for placing said supervisory relay under the control of said local subscriber's set. 60
- In witness whereof, I hereunto subscribe my name this 3rd day of December, A. D. 1919.
- WILLIAM H. BENDER NAGEL.
